UNITED STATES PATENT OFFICE.

WALTER JOHN TRAVIS, OF GARDEN CITY, NEW YORK.

GOLF-CLUB.

SPECIFICATION forming part of Letters Patent No. 739,458, dated September 22, 1903.

Application filed May 8, 1903. Serial No. 156,167. (No model.)

To all whom it may concern:

Be it known that I, WALTER JOHN TRAVIS, a citizen of the United States, residing at Garden City, Long Island, (post-office address 33 5 South William street, borough of Manhattan, city, county, and State of New York,) have invented certain new and useful Improvements in Golf-Clubs, of which the following is a specification, accompanied by drawings.

The invention relates particularly to the weighting of drivers, brassies, wooden putters, and other clubs wherein weight is added to a wooden or other club-head, which weight has usually been in the form of lead, molded or cast into the rear surface of the club-head.

The objects of the improvement are the attainment of precision in the manufacture of club-heads and in accurately locating the weight and also precision in the operation or 20 striking action of the club when in use.

It has been common in the most approved form of drivers and brassies to place the lead in an elongated groove or recess in the back of the head. In some instances two or three 25 separate holes have been drilled and the lead cast therein.

Numerous improvements have been made with varying success in the form and distribution of the lead mass, and many theoretical 30 considerations have been resorted to and applied in the attempt to improve the form of head. This present improvement is the result of a long series of observations made in actual practice of the game throughout the 35 principal links of the United States, which has resulted in the discovery of the present improvement, although I am not able even to-day to explain the theoretical principles involved with any certainty. The present

40 improvement, however, permits the more precise locating of the lead weight in constructing the club, because definite rules can be laid down and a definite method followed in forming the recess that is to receive the 45 weight; secondly, the improvement greatly increases the precision of the stroke, not only in the instance of the ball that is fully and fairly struck on the center of the face of the club, but also in the case of a ball struck

50 near either end of the striking-face of the club, the tendency to pull and slice being very

noticeably diminished by the improvement.

In the drawings several modifications of the invention are shown.

Figure 1 is a plan view of the driver-head, 55 showing the formation and position of the lead weight in section. Fig. 1^a shows the shape of the exposed surface of the lead at the rear of the club. Fig. 2 shows a modification. Fig. 3 shows a rear view of the same, and 6c Figs. 4, 5, and 6 show further modifications.

In Fig. 1, which shows the most preferred form of the invention, the weighting body of lead or other suitable material is placed directly in the line of stroke behind the center 65 of the face of the club; secondly, it is equally distributed laterally on both sides of such line; thirdly, the mass diverges inward within the head of the club, giving a spreading of the mass laterally as it nears the middle of the head; fourthly, the weight extends laterally within the head to points approximately directly behind the limits *p* and *s* of the club-face; fifthly, the shape of the weight is such that no anchors are required 75 to hold the lead or other weight in place, and, finally, the recess which contains the weight is of such shape and such symmetrical disposition that it may be accurately formed by the club-maker with certainty and without 80 danger of placing more of the weight at one end of the head than at the other, a result it has been next to impossible to attain with the usual curved recess of varying depth at the rear surface of the club-head.

Fig. 1^a shows the exposed surface of the lead at the rear of the club and also serves to show the thickness, which in the ordinary weight of the club-head may be from three-eighths to half an inch vertically.

In Figs. 2 and 3 the weight is of a somewhat different shape; but the recesses within which it is contained may be readily formed by drills in a simple and very accurate fashion. The limits, shape, amount of divergence, and 95 precise position of the two diverging arms of the lead mass are easily and accurately determinable in advance. Fig. 3 also serves to show the thickness of the lead vertically as well as horizontally.

In Fig. 4 a yet simpler outline of the lead mass is shown. The shape is seen in plan

view, being bounded by substantially straight lines and the lead mass diverging inward within the head of the club to points directly behind the limits *s* and *p* of the club-face.

5 Fig. 5 shows a modification, which differs from Fig. 4 in having the side walls of the recess curved in the manner shown.

Fig. 6 shows a convenient and advantageous form of the weight, which may be made 10 by first drilling into the head two crossed holes in the position shown in dotted lines and then gouging or chiseling out the spaces between the crossed holes, so as to form in a very direct and accurate fashion a recess of 15 the shape shown.

I disclaim any such invention in sectional golf-club heads as is shown in Briggs's patent, No. 552,042, wherein the weight is introduced between separate sections of a built-up club- 20 head without fulfilling the objects and purposes of my invention as herein set forth and claimed.

While my observations would seem to indicate that some of these forms of the invention are less advantageous than others and while manifestly some of the forms are more easily made than the others, nevertheless they all have common characteristics, as are pointed out in the broader of the following 25 claims, and they all of them in actual practice tend to direct the flight of the ball with more precision and with less danger of twisting, slicing, or pulling the ball than any other form of club-head with which I am familiar.

30 35 What I claim, and desire to secure by Letters Patent, is the following:

1. The improved weighted golf-club head having the weight set in from the rear of the club-head and placed centrally in line with 40 the face of the club and equally distributed laterally from the central line in a mass or masses diverging inwardly and spreading laterally as the center of the club-head is approached, said diverging portions extending 45 to and terminating at points substantially directly behind the lateral limits of the face of the club and said weight having an exposed surface at the rear of the club of less extent than the interior lateral dimension of 50 the weight, for substantially the purposes set forth.

2. The improved weighted golf-club head having the weight set in from the rear of the club-head and placed centrally in line with 55 the face of the club and equally distributed laterally from the central line in a mass or masses diverging inwardly and spreading laterally as the center of the golf-head is approached, said diverging portions extending 60 to and terminating at points substantially directly behind the lateral limits of the face

of the club, for substantially the purposes set forth.

3. The improved weighted golf-club head, having the weight set in from the rear of the 65 club-head and placed centrally in line with the face of the club and equally distributed laterally from the central line in a mass or masses diverging inwardly and spreading laterally as the center of the club-head is approached, for substantially the purposes set forth.

4. The improved weighted golf-club head, having the weight set in from the rear of the club-head and in the form of a mass extending inward from the rear of the club toward the center and diverging laterally as it approaches the center, for substantially the 75 purposes set forth.

5. The improved weighted golf-club head, 80 having the weighting mass set in from the rear of the club-head and of a form that is divergent inward and forward, thereby at once obviating the need of anchors and bringing the center of gravity farther forward in 85 the interior of the head, for substantially the purposes set forth.

6. In a golf-club of the class wherein the weight is inserted, as is common, from the rear, the improvement which consists in so 90 locating the weight-recess that it extends from the rear of the club forward and diverges laterally and is symmetrically located behind the striking-face of the club.

7. In a golf-club of the class wherein the 95 weight is inserted, as is common, from the rear, the improvement which consists in so locating the weight-recess that it extends from the rear of the club forward and diverges laterally and is symmetrically located 100 behind the striking-face of the club, said weight being secured solely by its shape fitting the said recess and thereby holding it in place.

8. The improved weighted golf-club head 105 of the class wherein the weight is set in from the rear of the club-head, said head having the weight centrally placed in line with the face of the club and equally distributed laterally from the central line in a mass or masses 110 diverging as the mass extends inward and forward, said weight being contained entirely within a recess in a single integral part of the head, for substantially the purposes 115 set forth.

In testimony whereof I have signed this specification in the presence of two subscribing witnesses.

WALTER JOHN TRAVIS.
